HEDDLE BAR FRAME

Marshall Memory Payne and Harvey Lee Sifford,
Kannapolis, N. C., assignors to Pioneer Atlanta
Company, Incorporated, Atlanta, Ga., a corpo-
ration of Georgia

Application August 18, 1937, Serial No. 159,770

5 Claims. (Cl. 139—92)

My invention relates to heddle bar frames, and more particularly to that type of frame which has a substantial length relative to its height, such as used in the weaving of wide fabrics.

In relatively long heddle frames, it has been the custom, and in fact a necessity to provide the heddle bars with one or more supports, intermediate of their end supports, so as to prevent undue sagging or twisting of the heddle bars due to the weight of the heddles and the vibration occasioned by the movement of the heddle frame when in operation.

Prior practice of supporting relatively long heddle bars intermediate of their ends, has included many forms of heddle bar supports or hooks. These known devices present many difficulties, owing to their unsatisfactory operation, multiplicity of parts which inherently involve probabilities of malfunction, and the cost of production thereof.

The present invention seeks to obviate the deficiencies of the known hooks or supports and contemplates the provision of a hook, one end of which is attached to the horizontal members of the heddle frame at spaced intervals and the other end of which is adapted to engage the heddle bars and maintain them in proper position, provision being made for a ready release of the heddle bar from the hook by a movement of the bar in a plane substantially at right angles to the direction of its length, whereby as a result of such movement the hook will be opened. The hook as herein disclosed does not require any manual opening of the hook per se to release the heddle bar.

Specific details of the present invention hereinafter appear, and will be more readily understood from the accompanying description, taken in connection with the accompanying drawing wherein:

Figure 1 is a side view of a heddle bar frame illustrating the invention in position to support the heddle bars.

Figure 2 is a side view of the hook in closed position.

Figure 2a is a side view of the hook in open position and illustrating the use of cam surfaces on the stationary and movable elements.

Figure 3 is a side view of the hook showing it in open position as a result of the raising of the heddle bar out of the slot.

Figure 4 is an end view of the hook illustrated in Figure 2.

Figure 5 is a side view of a hook for support-

ing two heddle bars in a single frame, one side of the hook being closed and the other side open.

Figure 6 is an end view of the double hook in a closed position.

The heddle frame per se, usually constitutes the horizontal upper and lower members 1 and 2, respectively, generally fashioned from wood, and end members 3 and 4 connecting the upper and lower members. The specific construction by which the top and bottom members and end members are connected is well known in the art and forms no part of the present invention.

The hook illustrated in Figures 2, 3 and 4, consists of a stationary element 5 and a movable element 6. The stationary element has one end fashioned into a screw-threaded shank 7 and its opposite end formed into a hook portion 8 arranged to provide the slot 10. The movable element 6 has one end connected to the stationary element by the pivot pin 11. The opposite end of the element 6 terminates in a hook portion 12 arranged to provide the slot 13.

The inward surface of the movable element 6 in the region of the pin 11 is provided with a cam surface 14, the formation and inclination of which is such that when the heddle bar 15 is moved toward the pivot and lifted clear of the slots 10 and 13, the edge of the heddle bar remote from the slot will begin to engage the cam surface 14. Continued movement of the heddle bar toward the pivot and in engagement with the cam 14 will cause the movable element 6 to swing to open position, as shown in Figure 3, whereupon the heddle bar is released.

The inner surface of the stationary element 5 may be provided with a cam surface 14a, as shown in Figure 2a, the formation and inclination of which is such that when the heddle bar is moved toward the pivot in the manner just described, the cam surface will move the heddle bar laterally, thus forcing the movable element 6 to open. Either or both elements may be provided with the cam surface heretofore described, the action of opening the hook being the same in all cases.

The above construction is equally adaptable to heddle frames which carry more than one heddle bar, as will be apparent from the following description. As shown in Figures 5 and 6, a stationary element 16 is provided with a screw threaded shank 17 for engagement with a horizontal member of the heddle frame. The opposite end of the stationary element terminates in the multiple hook portions 18 and 20 arranged to

provide the slots 21 and 22. The intermediate portion of the element 16 may be enlarged so as to provide a suitable bearing for the pivot pin 23 and the formation of cam surfaces hereinafter referred to.

Movable elements 24 and 25 have one end pivotally mounted on the pin 23 and the opposite end formed into the hook portions 26 and 27 arranged to provide the slots 28 and 30 which receive the 10 heddle bar. Cam surfaces 31 and 32 are formed on the inner surface of each hook element and these surfaces function in the same manner as described in connection with Figure 3. Similarly the stationary element may have its opposite 15 edges formed with cam surfaces in the same manner as the element 5 illustrated in Figure 2a.

What is claimed is:

1. In combination with a heddle frame and heddle bars carried thereby, a hook carried by 20 the frame and adapted to engage said bars comprising an element having one end attached to said frame and its opposite end provided with a slot for receiving a heddle bar, a complementary element pivotally connected to said first named 25 element provided with a slot for receiving a heddle bar, and means associated with said elements and engageable with the heddle bar for opening said elements upon a movement of the heddle bar in the plane of the slots and beyond the point 30 where said bar clears said slots.

2. In combination with a heddle frame and heddle bars carried thereby, a hook carried by the frame and adapted to engage said heddle bars comprising an element having one end attached to said frame and its opposite end provided with a slot for receiving a heddle bar, a complementary element pivotally associated with said first named element provided with a slot for receiving a heddle bar when the slot of said last 35 named element is in alignment with the slot of 40

the first named element, and a cam formed on one of said elements for opening the complementary element upon a movement of the heddle bar beyond the point where said bar clears said slots.

3. A heddle bar hook comprising a plurality of elements relatively movable to open and closed position provided at one end with slots for receiving a heddle bar when in closed position, and means associated with at least one of said elements and engageable with the heddle bar for moving said elements relatively to open position upon movement of the heddle bar in the plane of the slots and beyond the point where said bar clears said slots.

4. A heddle bar hook comprising a stationary element, a complementary element pivoted to said stationary element movable to open and closed position, said elements being provided at one end with slots for receiving a heddle bar when in closed position, a cam formed on the complementary element so fashioned and arranged that upon a movement of the heddle bar beyond a point where said bar clears said slot, the complementary element will be moved to open position.

5. A heddle bar hook comprising a stationary element, a plurality of complementary elements connected to said stationary element and movable to open and closed position, all of said elements being provided at one end with slots for receiving a heddle bar when in closed position, and means associated with at least two of said elements and engageable with the heddle bar for moving said elements relatively to open position upon a movement of the heddle bars in the plane of the slots 35 and beyond a point where said bars clear said slots.

MARSHALL MEMORY PAYNE.

HARVEY LEE SIFFORD.
